UNITED STATES PATENT OFFICE.

FRANK KUHN AND FRANK E. SHAILOR, OF DETROIT, MICHIGAN; SAID SHAILOR
ASSIGNOR TO SAID KUHN.

DESIGN FOR A BABY-FOOD WARMER.

47,698.

Specification for Design. Patented Aug. 10, 1915.

Application filed April 1, 1915. Serial No. 18,607. Term of patent 14 years.

To all whom it may concern:

Be it known that we, FRANK KUHN and FRANK E. SHAILOR, both citizens of the United States of America, residing at Detroit, in the county of Wayne and State of Michigan, have invented a certain new, original, and ornamental Design for Baby-Food Warmers, of which the following is a specification, reference being had therein to the accompanying drawings, forming part thereof, in which the figure is a perspective view of a baby-food warmer showing our new invention.

We claim:

The ornamental design for a baby food warmer, substantially as shown.

FRANK KUHN.
FRANK E. SHAILOR.
